UNITED STATES PATENT OFFICE

2,613,340

ELECTRON BEAM DEFLECTION AND REBALANCING APPARATUS

Waldo H. Kliever, Minneapolis, Minn., assignor to Minneapolis-Honeywell Regulator Company, Minneapolis, Minn., a corporation of Delaware

Application June 28, 1948, Serial No. 35,614

12 Claims. (Cl. 318—28)

1

The present invention relates generally to that type of apparatus for deflecting and rebalancing beams and in particular to that type of apparatus for deflection of the beam in a cathode ray tube and the rebalancing of the output of the tube.

It is an object of this invention to provide such a system whereby a novel magnet of simple construction produces deflection in accurate proportion to the extent of the controlling condition.

Another object is to provide such a system wherein the magnet is rotatable about the normal axis of the electron beam.

Another object is to provide such a system wherein the magnet is rotatable in a plane normal to the normal axis of the electron beam.

Another object is to provide such a system wherein the magnet may be endlessly rotatable.

One manner by which I accomplish the above objects is by using an endlessly rotatable circular permanent magnet having two inwardly extending pole pieces. This circular magnet is placed around the tube in which an electron beam is to be deflected.

The above mentioned objects may also be accomplished, in accordance with my invention, by positioning a bar magnet at the end of the cathode ray tube beyond the termination of the electron beam, said magnet being endlessly rotatable about the normal axis of the electron beam.

Another object of the invention is to provide novel means for reducing the signal sent to a load means to zero by rotating the tube about the normal axis of the electron beam in the tube. The energizing signal for rotating the tube may be obtained from the output of the tube plates.

Specific forms which the systems embodying the invention may take are shown in the accompanying drawings in which:

Figure 1 is a modification of the invention disclosing a circular endlessly rotatable magnet about a cathode ray tube and a feedback circuit for rotating the tube.

Figure 2 is a modification disclosing another manner of rebalancing the apparatus.

Figure 3 is a modification disclosing the use of an endlessly rotatable bar magnet to deflect the beam and still another manner of rebalancing, and

Figure 4 is a view taken along the line 4—4 in Figure 1 showing the shape of the circular magnet and its position with respect to the cathode ray tube.

Species of Figure 1

In Figure 1 is shown a cathode ray tube 10 having a filament 11 heating a cathode 12. An electron gun 13 controls the beam 14 and directs it toward the two target plates 15 and 16. The

2

beam 14 is modulated by means of an alternating voltage impressed between the cathode 12 and electron gun 13. The alternating voltage is supplied by a transformer 20 having a primary 21 and a secondary 22. The primary 21 of transformer 20 is energized from power leads 23 and 24 through leads 25 and 26.

A battery 30 energizes the cathode ray tube by impressing a voltage between the plates 15 and 16 and the cathode 12. A portion of the battery 30 is also used to place a positive potential on the electron gun 13 with respect to cathode 12 by the following circuit; cathode 12, lead 31, transformer secondary 22, that portion of battery 30 between transformer secondary 22 and terminal 32, lead 33, and electron gun 13. The potential applied between the plate 15 and the cathode 12 is by the following circuit; cathode 12, lead 31, transformer secondary 22, battery 30, lead 34, resistor 35, lead 36 and plate 15. The potential impressed between cathode 12 and plate 16 is by the following circuit; cathode 12, lead 31, transformer secondary 22, battery 30, lead 34, resistor 37, lead 38 and plate 16.

A controlling member 40 is connected by a mechanical drive 41 to a gear 42. The controlling member may be either manually operated or operated by some condition responsive element such, for example, as a bimetallic element. The gear 42 meshes with segments on the outer edge of a circular magnet 43, better shown in Figure 4.

In Figure 4 the circular magnet 43 is shown surrounding the envelope 10 on the cathode ray tube. Two inwardly projecting portions 44 and 45 of the magnet are shown, these being the north and south magnetic terminals. As shown and described magnet 43 is a permanent magnet. The controlling member 40 could be capable of continuously rotating gear 42 and thus magnet 43.

Means for mounting the magnet 43 are shown in Figure 4 as two guiding rollers 46 and 47 which are, with gear 42, spaced about magnet 43 to support the magnet about the tube. It is understood, however, that the supporting means may be any means commonly used for mounting an endlessly rotatable circular member about another.

The output of the cathode ray tube is applied from plates 15 and 16 through the leads 36 and 50 and leads 38 and 51 to amplifier 52. This amplifier may be any amplifier suitable for taking two signal inputs, comparing them, amplifying the difference in signals, and supplying an output reversible in phase to one winding of a reversible motor. A suitable amplifier for this purpose is shown in an Upton Patent 2,423,534 having the same assignee as the present application. The amplifier is grounded at point 53 while the cathode 12 in the cathode ray tube 10 is grounded at ground 17. This permits electrons to flow in

the circuit from cathode 12, cathode ray tube beam 14, plates 15 and 16, leads 36 and 50 and leads 38 and 51, amplifier 52, ground 53, ground 17, and lead 31 back to cathode 12. The amplifier 52 is energized from power leads 23 and 24 by leads 54 and 55.

The amplifier output is fed through leads 56 and 57 to a motor winding 60 of a capacitor motor 61, said motor winding 60 having a condenser 62 in parallel therewith. A second motor winding 63 of motor 61 is in series with a phase shifting condenser 64 and is energized from power leads 23 and 24 through leads 65 and 66. Due to the condenser 64 and the connections within the amplifier, the current supplied to winding 60 by amplifier 52 will either lead or lag by 90° that flowing through winding 63, depending upon the phase of the output of amplifier 52, and motor 61 will rotate in one direction or the other depending upon the direction of the phase displacement. The armature 67 of motor 61 is connected by means of mechanical connections 70 and 76 and gear reduction unit 77 to a gear 71. The gear 71 is connected with a gear 72 rigidly fastened to the envelope 10 of the cathode ray tube.

Armature 67 is further connected by mechanical connections 70, 76 and 73 and gear reduction box 77 to a pointer 74 on a dial 75, said pointer rotating with gear 72 and indicating the direction in which the magnet 43 is directing the beam 14.

Operation of Figure 1

The operation of the system shown in Figure 1 with the magnet 43 in the position indicated is as follows.

The electron beam leaves the cathode 12, passes through the electron gun 13, and then enters the magnetic field of the magnet 43. The lines of flux in the magnetic field are from North to South and causes the electron beam to be deflected toward the right but it will still impinge equally on plates 15 and 16.

Now if the magnet should be rotated slightly to cause a greater portion of the electron beam to strike plate 15 and a smaller portion of the beam to strike plate 16 there will be a difference in the signal input from the two plates to the amplifier 52.

This signal input difference will be amplified and an alternating current output will be sent to motor winding 60 of motor 61, the phase of which will depend upon the phase relationship of the amplifier input voltage to the amplifier power supply voltage. As motor winding 63 is continuously energized energization of the motor winding 60 will cause rotation of armature 67 in a direction dependent upon the direction of deflection of the beam, causing rotation of gear 71 and thus gear 72 until the cathode ray tube has been rotated to the position shown in the drawing in which position, the cathode ray beam 14 will impinge equally on plates 15 and 16 and thus the signal difference input to the amplifier 52 will again be reduced to zero.

If now magnet 43 is moved in the opposite direction by member 40, the beam 14 will be deflected in the opposite direction toward plate 16 and thus the signal output to motor winding 60 will be of the opposite phase with respect to the voltage across winding 63 as compared to the phasing described in the preceding condition, and the armature 67 will rotate in the opposite direction.

Species of Figure 2

In Figure 2 is shown a modification wherein

four plates 80, 81, 82 and 83 may be used instead of the two plates as shown in Figure 1. Many of the components used in the circuit shown in Figure 2 are the same as those shown in Figure 1 and have been indicated by similar numbers.

The plate supply battery 39 is connected to the four plates as follows:

Positive terminal of battery 39, lead 84, resistance 85, lead 86 and plate 80; positive terminal of battery 39, lead 84, resistance 87, lead 88, and plate 81; positive terminal of battery 39, lead 84, resistance 90, lead 91 and plate 82; and positive terminal of battery 39, lead 84, resistance 92, lead 93 and plate 83.

Plates 80 and 82 are connected to opposite terminals of a potentiometer 94 through leads 86 and 95 and leads 91 and 96 respectively. Plates 81 and 83 are connected to opposite terminals of a potentiometer 97 through leads 88 and 98 and leads 93 and 99, respectively. The potentiometers 94 and 97 are center tapped to ground at 100 and 101 respectively. Potentiometer 94 has a wiper arm 102 and potentiometer 97 has a wiper arm 103. Wiper arms 102 and 103 are connected to amplifier 52 through leads 104 and 105 respectively. As seen in the drawing the two potentiometers 94 and 97 are wound at right angles to each other while the wiper arms 102 and 103 are rotated in parallel with each other. It is understood, of course, that the potentiometer windings may be parallel and the wiper arms at right angles.

The voltage across each potentiometer varies according to the deflection of the beam. The variation is according to the sine and cosine of an angle from a proper reference line. The terminals of the winding of potentiometer 94 are of equal positive and negative polarity with respect to the grounded center tap 100, and the terminals of the winding of potentiometer 97 are of equal positive and negative polarity with respect to the grounded center tap 101, but the terminal potentials of the two potentiometers will vary and will be equal to each other only at the angles of 45°, 135°, 225° and 315°. There will always be one point on each winding, however, at which there will be no potential difference, and a second pair of points on the two windings at 180° angle from the first pair of points at which there will also be no potential difference. When the two wiper arms are at one of these pairs of points, there will be no signal applied to the amplifier 52.

If the potentials on the two wiper arms 102 and 103 are not the same with respect to ground, the signal difference input into amplifier 52 will be amplified and applied to motor winding 60 of motor 61. The resulting energization of winding 60 of motor 61 will cause rotation of armature 67 resulting in rotation of wiper arms 102 and 103 through mechanical connections 106 and 107 between the armature 67 and the aforesaid wiper arms. When the wiper arms 102 and 103 have been rotated to such an extent that the potential of these two wiper arms with respect to ground are equal, the signal difference input to the amplifier will be reduced to zero and will cause the rotation of armature 67 of motor 61 to cease.

A more detailed description and use of the two potentiometers 94 and 97 is contained in my co-pending application, Serial No. 793,819, filed December 26, 1947 and assigned to the present assignee. These potentiometers are referred to in the above mentioned application as sine resistors and cosine resistors.

design and effect of a second type of modification of the invention of Figure 3 is shown in

Species of Figure 3.

In Figure 3 another modification is shown, wherein many of the components used are the same as those shown in the first two figures. In Figure 3, however, the magnet is a bar magnet 110 and is shown placed at the end of the cathode ray tube beyond the target plates. It is understood, of course, that the magnet 110 may be placed at the other end of the tube 10 as well and that it has been shown placed beyond the target plates merely for convenience. The amount of deflection of the electron beam 14 due to the magnet is dependent upon the distance of the magnet from the cathode. This is true because the closer the magnet is to the cathode the greater the deflection of the beam immediately upon leaving the cathode. The bar magnet 110 is connected to a controlling member 111 through a mechanical connection 112 and is also endlessly rotatable as is the circular magnet 43 shown in Figures 1 and 2. The bar magnet 110 has the same effect upon the electron beam 14 as does the circular magnet 43. In this species of the invention, a coil 117 is employed to deflect the beam to rebalance the system. This coil is connected to the output terminals of amplifier 58 by a circuit including an ammeter 115. In the position shown the magnet 110 will cause the electron beam 14 to be deflected to the right, but the beam 14 will still be proportioned equally between the plates 15 and 16. As a result no signal will be sent from the plates to the amplifier 58. Amplifier 58 differs from amplifier 52 in that whereas amplifier 52 uses an A. C. power source and an A. C. signal to produce an A. C. output, the amplifier 58 in Figure 3 uses an A. C. power source and an A. C. signal to produce a D. C. output of variable magnitude. It is to be understood that the output of amplifier 58 may be reversed in polarity. An amplifier which will answer this purpose is shown in a Wills Patent 2,256,304 and assigned to the same assignee as the present invention.

If the magnet 110 is rotated slightly the corresponding deflection of the beam 14 will cause a greater portion of the beam to impinge upon one of the plates and a lesser portion of the beam to impinge upon the other plate, thus causing a signal input to the amplifier 58. The output of the amplifier will be applied through leads 113 and 114, indicator ammeter 115, and lead 116 to a balancing coil 117. The balancing coil 117 remains fixed in position, but the current therethrough is dependent upon the unbalance of the electron beam striking the plates. With a small signal input to the amplifier 58, a small current will be sent through the coil 117 which will send out a weak magnetic field. This will, however, be sufficient to reduce the deflection of the electron beam. The amount of current through the balancing coil 117 determines the strength of the balancing flux field. This current will be determined by the constants of the amplifier. It is to be noted, however, that if the deflection of the electron beam be reduced to zero there will be no amplifier output to the coil 117 and thus the bar magnet 110 would again deflect the beam away from center. The balancing coil 117 does not completely reduce the deflection of the beam to zero but rather reduces it to the point where that component of the magnetic field due to the bar magnet, which is perpendicular to the adjacent edges of the plates 15 and 16, will be balanced by the magnetic field

due to the balancing coil 117. The ammeter is placed in the balancing coil circuit merely to indicate the amount of deflection of the electron beam, and because of this may have a dial calibrated in terms of the beam deflection placed thereon.

It is to be understood that the invention herein disclosed is not considered to be limited to the modification herein described, but is rather limited only to the extent of the claims hereto appended.

I claim as my invention:

1. In combination: means for directing an electron beam along an axis; target means disposed about said axis for impingement by said beam; deflecting means having spaced, opposed poles to provide a directed field to deflect said beam from said axis to produce a signal on said target means; means mounting said deflecting means for rotation about an axis perpendicular to said field and aligned with said axis of said beam; and means responsive to a condition to be sensed to position said deflecting means in accordance with the value of said condition.
2. In combination: means for directing an electron beam along an axis; target means disposed about said axis for impingement by said beam; deflecting means having spaced, opposed magnetic poles to provide a directed field to deflect said beam from said axis to produce a signal on said target means; means mounting said deflecting means for rotation about an axis perpendicular to said field and aligned with said axis of said beam; and means responsive to a condition to be sensed to position said deflecting means in accordance with the value of said condition.
3. In combination: target means disposed about an axis for impingement by an electron beam; means for directing said electron beam along said axis to energize said target means; deflecting means having spaced, opposed poles to provide a directed field to deflect said beam from said axis to vary the relative energization of said target means in accordance with the amount of deflection of said beam from said axis; means responsive to the change of relative energization of said target means; means mounting said deflecting means for rotation about an axis perpendicular to said field and aligned with said axis of said beam; and means responsive to a condition to be sensed to position said deflecting means in accordance with the value of said condition.
4. In combination: target means disposed about an axis for impingement by an electron beam; means for directing said electron beam along said axis to energize said target means; deflecting means having spaced, opposed poles to provide a directed field to deflect said beam from said axis to vary the relative energization of said target means in accordance with the amount of deflection of said beam from said axis; means responsive to the change of relative energization of said target means; follow-up means to restore the initial energization of said target means; means mounting said deflecting means for rotation about an axis perpendicular to said field and aligned with said axis of said beam; and means responsive to a condition to be sensed to position said deflecting means in accordance with the value of said condition.
5. In combination: means for directing an electron beam along an axis; a plurality of target plates disposed about said axis for impingement

by said beam; deflecting means having spaced, opposed magnetic poles to provide a directed field to deflect said beam from said axis to produce signals of different magnitudes on said target plates; means mounting said deflecting means for rotation about an axis perpendicular to said field and aligned with said axis of said beam; a responsive device electrically connected to said target plates to receive a signal therefrom; follow-up means, dependent on the signal to said responsive device, for reducing the signal to said responsive device to a minimum; and means responsive to a condition to be sensed to position said deflecting means in accordance with the value of said condition.

6. In combination: means for directing an electron beam along an axis; a plurality of target plates disposed for impingement by said beam; a circular magnet mounted symmetrically about the normal axis of said beam in a plane normal thereto and endlessly rotatable about said beam for deflecting said beam to produce signals of different magnitudes on said target plates; means rotating said magnet in response to a condition; a responsive device electrically connected to said target plate to receive a signal therefrom; and means, dependent upon the signal to said responsive device, for reducing the signal to said responsive device to a minimum.

7. In combination: means for directing an electron beam along an axis, target means disposed about said axis for impingement by said beam, deflecting means for deflecting said beam from said axis to produce a signal on said target means, and means for mounting said deflecting means symmetrically about the normal axis of said beam in a plane normal thereto beyond the termination of said beam on said target means and rotating said deflecting means about said axis in response to a condition through an angle dependent in value on said condition.

8. In combination: means for directing an electron beam along an axis; a plurality of target plates disposed about said axis for normally equal impingement by said beam; means for deflecting said beam from said axis to produce unequal impingement on said target plates; means for mounting and rotating said deflecting means; and load means for utilizing a signal dependent in magnitude upon the extent of said unequal impingement to rotate said target plates around said axis to cause the beam to equally impinge on said target plates.

9. In combination: means for directing an electron beam along an axis; a plurality of target plates disposed about said axis for normally equal impingement by said beam; means for deflecting said beam from said axis to produce unequal impingement on said target plates; means for mounting said deflecting means symmetrically about the normal axis of said beam in a plane normal thereto and endlessly rotating said deflecting means about said axis; and load means for utilizing a signal dependent in magnitude upon the extent of said unequal impingement to rotate said target plates around said axis to cause the beam to equally impinge on said target plates.

10. In combination: means for directing an electron beam along an axis; a plurality of target plates disposed about said axis for normally equal

impingement by said beam; a circular magnet for deflecting said beam from said axis to produce unequal impingement on said target plates; means for mounting said magnet symmetrically about the normal axis of said beam in a plane normal thereto and endlessly rotating said magnet about said axis; and load means for utilizing a signal dependent in magnitude upon the extent of said unequal impingement to rotate said target plates around said axis to cause the beam to equally impinge on said target plates.

11. In combination: means for directing an electron beam along an axis; a plurality of target plates disposed about said axis for normally equal impingement by said beam; deflecting means for deflecting said beam from said axis to produce a signal by unequal impingement on said target plates; means for mounting said deflecting means symmetrically about the normal axis of said beam in a plane normal thereto beyond the termination of said beam on said target plates; said deflecting means being endlessly rotatable about said axis by means operating in response to a condition; and load means for utilizing a signal dependent in magnitude upon the extent of said unequal impingement to rotate further magnetic means around said axis to reduce the unequal impingement on said target plates to a minimum.

12. In combination: means for directing an electron beam along an axis; a plurality of target plates disposed about said axis for impingement by said beam; a circular magnet mounted symmetrically about the normal axis of said beam in a plane normal thereto and endlessly rotatable about said axis for deflecting said beam from said axis to cause said beam to unequally impinge said target plates; means rotating said magnet in response to a condition; a responsive device electrically connected to said target plates to receive a signal therefrom dependent in magnitude upon the extent of said unequal impingement; and means, dependent upon the signal to said responsive device, to rotate said target plates around said axis to cause said beam to equally impinge on said target plates.
